UNITED STATES PATENT OFFICE.

WILLIAM L. KELLOGG, OF DETROIT, MICHIGAN.

TANK-CAR ANCHOR.

1,290,574.

Specification of Letters Patent.

Patented Jan. 7, 1919.

Application filed July 13, 1917. Serial No. 180,258.

To all whom it may concern:

Be it known that I, WILLIAM L. KELLOGG, a citizen of the United States, residing at Detroit, in the county of Wayne and State 5 of Michigan, have invented a certain new and useful Improvement in Tank-Car Anchors, of which the following is a full, clear, concise, and exact description, reference being had to the accompanying drawings, 10 forming a part of this specification.

This invention relates to improvements in tank car anchors.

The object of the invention is to provide simple means for detachably yet rigidly 15 anchoring the tank of a tank car to the car underframe and more specifically, to provide a strong and durable anchor of the type indicated wherein are employed wedge-acting, dovetail keys for securing the anchor 20 plate of the tank to the anchor plate of the underframe.

In the drawing forming a part of this specification, Figure 1 is a side elevation of a portion of a tank car showing the tank, a 25 portion of the center sills and the anchoring means. Fig. 2 is a bottom plan view of the anchor plate or member which is secured to the tank. Fig. 3 is a top plan view of the anchor member or plate which is secured to 30 the center sills. Fig. 4 is a longitudinal sectional view, upon a larger scale, illustrating more particularly the details of the anchor means. Fig. 5 is a vertical, trans- 35 verse, sectional view, taken substantially on the line 5—5 of Fig. 4. Fig. 6 is a similar sectional view, taken on the line 6—6 of Fig. 4. Fig. 7 is a view corresponding to Fig. 4 but illustrating another embodiment 40 of the invention. And Fig. 8 is a trans- 45 verse, vertical, sectional view, taken substantially on the line 8—8 of Fig. 7.

In said drawings, and referring to the construction illustrated in Figs. 1 to 6 inclusive, 10—10 denote channel-shaped center 45 sills of a tank car underframe, said sills being arranged in the usual manner, that is, with their flanges extended outwardly. The tank, which may be of any desired form, is designated generally by the reference A.

50 The means for anchoring the tank to the center sills of the underframe comprise, broadly, an anchor plate or member B secured to the tank, an anchor plate C secured to the center sills, and a pair of keys D—D.

55 The tank anchor plate B is preferably in

the form of a casting of general rectangular formation curved on its upper face, as indicated at 12, to fit the under side of the tank and having flanges 13 by which it is riveted thereto. The casting or plate B 60 is provided with a central opening 14 to accommodate the discharge valve and other mechanism of the tank car and on its under face, said plate B is provided near its ends with a pair of undercut transversely extending grooves of dovetail formation 15—15. Also on its lower face and intermediate the dovetail grooves 15 and on opposite sides of the opening 14, said plate B is provided 65 with a series of slots or recesses 16—16 ex- 70 tends transversely of the casting and open at their ends.

The underframe anchor plate C is pro- 75 vided with a pair of depending flanges 17—17 which fit against the inner faces of the center sills 10 and are riveted thereto. On its upper face, the plate C is recessed 80 along its outer edges at intervals, as indicated at 18—18, so that said plate can be riveted to the top flanges of the center sills, as indicated by the rivets 19—19. Near its ends and adapted to aline with the undercut grooves 15 of the tank anchor plate B, the plate C is provided with corresponding 85 undercut or dovetail shaped grooves 20—20. On its upper face and intermediate the grooves 20—20, the plate C is provided with a plurality of upstanding transverse ribs or 90 projections 21—21 which are adapted to fit within the said recesses 16 in the plate B. The plate C is also provided with a central opening 22 to correspond to said opening 14.

The tank A is applied to the underframe by lowering the same with its anchor plate B on top of the anchor plate C and so that the ribs 21 fit within the corresponding recesses 16. This brings the dovetail slots or grooves 15 and 20 into alinement and the double dovetail keys D—D are inserted transversely. Each set of grooves 15 and 20 and the keys D are preferably tapered lengthwise and also slightly in thickness and in actual practice, the lengthwise taper of the grooves and keys of one set is reversed 100 with respect to the other set. The keys D 105 are held against accidental displacement by any suitable means, such as cotters 23, passed through their smaller ends, as indicated most clearly in Fig. 6.

The construction above described and 110

illustrated in Figs. 1 to 6 inclusive, is what is generally known as a "one-point" anchor, that is, the anchor is located at the center of the tank. In the construction illustrated 5 in Figs. 7 and 8, the anchor is of the "two-point" type. In this construction, two sets of anchor plates B' and C are provided which are separated the desired distance and secured, respectively, to the tank and 10 center sills. In this construction I provide a dowel pin arrangement, as indicated at 121 in Fig. 8, but instead of extending the locking keys transversely of the car, the same are preferably extended lengthwise, as 15 shown by the double dovetail keys D', most clearly illustrated in Fig. 8. In this construction, one key is inserted from each end.

With the anchoring means, above described, it is obvious that the tank can be 20 quickly and rigidly attached to the underframe. The ribs and recesses 21 and 16 or dowel pin arrangement provides the necessary shearing area to prevent shifting of the tank longitudinally or transversely relatively to the underframe. On account of the 25 use of double dovetail keys D and D', the two anchor plates are effectively protected from vertical separation, and in addition, it will of course be understood that said 30 keys provide shearing area against either longitudinal or transverse shifting, depending upon the location of said keys. Furthermore, the attachment of the anchor plate C to the center sills is such as to not 35 only secure a strong union therebetween but also to effectively brace the center sills and materially increase their resistance to shocks. By tapering the keys D and D' and their corresponding slots, the parts will be pulled 40 together very tightly and any looseness or play of the parts completely eliminated.

Although the preferred form of the invention has herein been shown and described, the same is merely illustrative and 45 all changes and modifications are contemplated that come within the scope of the claims appended hereto.

What is claimed is:

1. In a car having a tank and an under- 50 frame, means for detachably connecting the tank to the underframe including, an anchor plate secured to the tank, an anchor plate secured to the underframe, and a dove-

tail shaped key detachably connecting said plates.

55

2. In a car having a tank and an underframe, means for detachably connecting the tank to the underframe including anchor plates secured to the tank and the underframe respectively, said plates being provided with alined dovetail grooves, and a double dovetail key coöperating with said grooves for detachably uniting said plates.

60

3. In a car having a tank and an underframe, means for detachably connecting the tank to the underframe, including, anchor plates secured respectively to the tank and underframe, said plates having coöperating, transversely extending ribs and recesses on their adjacent faces to prevent relative 70 longitudinal shifting of the tank and underframe, and detachable means for preventing vertical separation of the plates.

65

4. In a car having a tank and an underframe, means for detachably connecting the tank to the underframe including, anchor plates secured respectively to the tank and underframe, said plates having coöperating, transversely extending ribs and recesses on their adjacent faces to prevent relative longitudinal shifting of the tank and underframe, and detachable means for preventing vertical separation of the plates, said means including a double dovetail key.

75

5. In a car having a tank and an underframe, means for detachably connecting the tank to the underframe including, an anchor plate secured to the tank, an anchor plate secured to the underframe, and a dovetail shaped key detachably connecting said 90 plates, said key being tapered in the direction of its length.

85

6. In tank car construction, the combination with center sills and a tank, of anchor plates secured respectively to the tank and 95 underframe, said anchor plates having alined, transversely extending dovetail slots, and a double dovetail key insertible within said slots for detachably uniting said anchor plates and to prevent vertical separation.

100

In witness that I claim the foregoing I have hereunto subscribed my name this 26th day of June, 1917.

WILLIAM L. KELLOGG.
